UNITED STATES PATENT OFFICE.

DANIEL B. WARE, OF ATHENS, MICHIGAN.

BED ATTACHMENT.

SPECIFICATION forming part of Letters Patent No. 588,622, dated August 24, 1897.

Application filed November 4, 1896. Serial No. 611,016. (No model.)

To all whom it may concern:

Be it known that I, DANIEL B. WARE, a citizen of the United States, residing at Athens, in the county of Calhoun and State of Michigan, have invented certain new and useful Improvements in Bed Attachments; and I do hereby declare the following to be a full, clear, and exact description of the invention, such as will enable others skilled in the art to 10 which it appertains to make and use the same.

This invention relates to improvements in bedsteads, and has more particular relation to back-rests for the same.

The invention consists of certain novel constructions, combinations, and arrangements of parts, all of which will be hereinafter more particularly set forth and claimed.

In the accompanying drawings, forming part of this specification, Figure 1 represents 15 the head of a double bed, one of the adjustable panels being in operative position; and Fig. 2 represents a central vertical section through said head on the line of the inclined panel.

20 A in the drawings represents the head proper of the bedstead; B B, the adjustable panels. Said head A is provided with the usual supporting-legs a and has two panel-receiving recesses a' a' formed in its front 25 face, with a central bar a² dividing the same. The side walls of the upper portions of the recesses a' are grooved, as at a³, and notched plates a⁴ applied therein. The said upper ends of the panels B are provided with laterally-projecting studs b b, adapted to slide 30 within the grooves a³ and be secured in any desired notches in the bars a⁴. The lower ends of the panels are each provided with two notched segmental bars b' b', arranged 35 on opposite sides of the same. The notches in said bars are provided with a straight side b² and an inclined side b³, so that as the forward ends of said panels B are pulled out the bars b' will readily ride over the laterally-projecting studs b⁴, mounted upon the frame 40 of the head, but upon any reverse movement will become lodged upon said studs by the vertical wall b², engaging the same. The said bars are adapted to work in slots b⁵ b⁵, formed 45 in the frame of the head.

It will be observed from the foregoing description that when the panels B are in their

normally-closed position they will lie altogether within their respective recesses in the head and will present the appearance of ordinary ornamental panels. When it is desired to use either one or the other of the panels as an inclined rest for the back for an invalid or a person desiring to read while lying in bed, the lower end of the panel is 55 pulled forward, causing the bars b' to ride over the studs b⁴ until the proper adjustment is secured, when the notches in said bars fall over said studs and hold the panel in the desired adjusted position. As the lower end 60 of said panel is pulled outward the studs b descend in the grooves a³, and when a desired adjustment has been reached the said studs b are forced into the proper notches of the bars a⁴. At the same time the notched bars 65 b' are raised slightly, so as to disengage them from the studs b⁴ and permit the lower end of the panel to be pushed inward. When the panel has been returned to its normal position, the said bars b' project down below the 70 bed out of sight.

If so desired, one or both of the panels B may be upholstered, as shown in the drawings, so that a soft and yielding support is 75 provided for the back.

It will also be observed that with my invention, while the panels normally occupy such a position as to be altogether withdrawn into the head and excite no suspicion of their real utility, they may be instantly withdrawn 80 from their respective recesses when so desired and adjusted in any inclined position desired, thereby forming a comfortable support for the back.

Having thus described my invention, what 85 I claim as new, and desire to secure by Letters Patent, is—

1. The combination with the head of a bedstead of a panel movably mounted therein and provided at its lower end with segmental 90 notched adjusting-bars, projections mounted upon said head and adapted to support said notched bars, and means for adjustably connecting the upper end of said panel with the head; the construction and operation being 95 such that the lower portion of the panel may be pulled outward and automatically located in its adjusted position by the gravity of the segmental bars causing the projections on the 100

head to engage other notches, substantially as described.

2. The combination with the head of a bed-
stead of a movable panel mounted therein,
notched bars rigidly secured to said head,
lateral projections on the upper end of said
panel adapted to engage said notched bars,
segmental notched bars pivotally connected
to the lower end of said panel, and projec-
tions formed upon the head and adapted to
support said segmental bars; the construc-
tion and operation being such that the notched
bars automatically lock with the projections
on the head by their own inherent gravity.
- 15 3. The combination with the head of a bed-
stead provided with a plurality of panel-re-
cesses, of vertical notched bars mounted in
said recesses, movable panels also mounted

in said recesses, and provided with lateral
projections adapted to engage said notched 20
bars, notched segmental bars pivotally con-
nected to the respective opposite sides of the
lower ends of each panel, and projections
formed on the head and adapted to support
said notched bars; the construction and op- 25
eration being such that the segmental bars
automatically lock with said projections by
their own inherent gravity when the panels
are adjusted, substantially as described.

In testimony whereof I have signed this 30
specification in the presence of two subscrib-
ing witnesses.

DANIEL B. WARE.
